UNITED STATES PATENT OFFICE.

JAMES CLEMENT BUTLER, OF QUINCY, ILLINOIS, ASSIGNOR OF ONE-HALF
TO EZRA BEST, OF SAME PLACE.

SMOKE-CONSUMER.

SPECIFICATION forming part of Letters Patent No. 404,775, dated June 4, 1889.

Application filed March 18, 1889. Serial No. 303,692. (No model.)

To all whom it may concern:

Be it known that I, JAMES CLEMENT BUTLER, of Quincy, in the county of Adams and State of Illinois, have invented a new and useful Improvement in Smoke-Consumers, of which the following is a specification.

My invention consists in a new and improved smoke-consumer, which will be hereinafter fully described and claimed.

Referring to the accompanying drawings, Figure 1 is a front view of the furnace to which my invention is shown as applied. Fig. 2 is a side elevation with parts of the furnace broken away. Fig. 3 is a sectional view taken on the plane indicated by line x x of Fig. 2; and Figs. 4 and 5 are detail views, which will be hereinafter referred to.

The same letters of reference indicate corresponding parts in all the figures.

In the accompanying drawings I have shown my invention applied to a stationary steam-boiler furnace.

Referring to the several parts by letter, A indicates a steam-boiler, and A' the dome of the same. B indicates the front of the furnace; C, the grate; and D the bridge-wall, which will be hereinafter more particularly referred to. Beneath the boiler are arranged in the bridge-wall three tile flues E, that being the number used in the boiler here illustrated. These tile flues E are each ten inches in diameter at their front ends and taper to nine inches diameter at their rear ends, and are each thirty-two inches long, said flues to be increased or diminished in size according to the size of the boiler and the space required in the furnace.

F indicates the main pipe, which passes through the bridge-wall below the grate, and which consists of a hollow tube or pipe two inches in diameter, (the size of this and the other pipes hereinafter described varying according to the service required.) Upon the outer end of this main pipe, which extends out beyond the bridge-wall under the grate, as shown, is screwed or otherwise secured a cap G, which is formed with a central aperture G', three-eighths of an inch in diameter, and a series of smaller apertures G² to admit air into the pipe, and arranged, preferably, in a circle around the central aperture.

The main pipe F passes entirely through

the bridge-wall below the grate, and at its rear end is connected by the T with the auxiliary or branch pipes H H. These branch pipes are one-and-one-fourth inch in diameter and extend up back of the bridge-wall, and then forward through the bridge-wall on a line with the center of the tile flues E, as most clearly shown in Fig. 3 of the drawings.

A steam-pipe I leads from the dome of the boiler down in front of the furnace to a point below the grate C, where it passes through the front of the furnace, and its lower end I' enters the front end of the main air-pipe F through the central aperture G' of the cap G. The end I' of the steam-pipe extends from three to five inches within the front end of the main air-pipe, and is reduced in size, as shown in the drawings, tapering from three-eighths to three-sixteenths of an inch in diameter, thus acting as an injector, injecting and forcing the air into the furnace.

It will be seen that the current of steam brought through the pipe I from the dome of the boiler will force a steady current of air through the pipes into the furnace with the steam, and the steam, after entering the pipes F and H H, will become superheated and is not visible in the furnace, and will cause the combustion to be complete, consuming all the gases which ordinarily pass off in huge volumes of black smoke.

The bridge-wall extends up close around the boiler, as clearly shown in Fig. 3 of the drawings, and will confine the heat and gases to the flues, thereby bringing the air and superheated steam brought through the pipes F and H H in direct contact with the gases upon entering the furnace. The steam-pipe is provided with valves I², by means of which the amount of steam flowing through the pipe can be regulated as required.

J indicates a brick floor or way arranged longitudinally below the boiler, inclined downward toward the furnace, as shown in Fig. 2, so that its forward end is just below the inner end of the tile-flues E, and running back to the soot-pit K.

By reason of the perfect combustion, there is no accumulation of soot to become ignited and burn out stock, thereby greatly diminishing the danger and liability of fire. This is an important feature.

From the foregoing description, taken in connection with the accompanying drawings, the construction, operation, and advantages of my invention will be readily understood.

5 It will be seen that while it is comparatively simple and also inexpensive in construction it will cause a perfect combustion of all the gases which would otherwise pass off in huge volumes of black smoke, thus effecting a most 10 important object, and that by reason of this perfect combustion there will be no accumulation of soot to become ignited. The invention can of course be applied to all classes of horizontal boilers.

15 Having thus described my invention, what I claim, and desire to secure by Letters Patent, is—

1. The combination, with a boiler and the furnace and bridge-wall of the same, of flues 20 leading through the bridge-wall, a main pipe passing through the bridge-wall below the furnace-grate, branch pipes leading from the main pipe up and forward through the bridge-wall above the furnace-grate, and a steam- 25 pipe leading from the boiler-dome to the main pipe.

2. The combination, with a boiler and the

furnace and bridge-wall of the same, of flues leading through the bridge-wall, the main pipe and the branch pipes, the apertured end 30 cap, and the steam-pipe, substantially as set forth.

3. The combination, with a boiler and the furnace and bridge-wall of the same, of flues 35 leading through the bridge-wall, the main pipe and the branch pipes, the apertured end cap, and the steam-pipe having the tapering lower end, substantially as set forth.

4. The combination, with a boiler and the furnace and bridge-wall of the same, of the 40 tapering flues, the main pipe having the apertured end cap, the branch pipes, and the steam-pipe having the tapering lower end, substantially as set forth.

5. The combination, with a boiler and the 45 furnace and bridge-wall of the same, of the tapering flues, the inclined floor, the main pipe having the apertured end cap, the branch pipes, and the steam-pipe, substantially as set forth.

JAMES CLEMENT BUTLER.
